PITCHER MANIKIN

Clarence A. Schuyler, Chicago, Ill., assignor to
 H. C. Evans & Co., Inc., Chicago, Ill., a corpora-
 tion of Illinois

Application October 8, 1941, Serial No. 414,060

4 Claims. (Cl. 46—145)

This invention relates to amusement and game apparatus and has for its principal object the provision of a manikin of an improved structure which is economical and simple in manufacture and highly efficient in use.

An object of the present invention is to provide a manikin structure having a fixed nether portion and a movable trunk portion and novel mechanism for imparting movement to the trunk portion to simulate a bending action for the purpose of picking up a ball to be projected.

Another object of the present invention is the provision of an improved manikin having a pivoted arm adapted to swing about the shoulder of the manikin for the purpose of pitching a ball disposed in the hand portion of said arm.

Another object of this invention is the provision in a bendable manikin structure having a swinging arm for pitching a ball, of a flexible link for rotating the arm in swinging motion to impart a ball pitching action in said arm.

Other objects, advantages and novel aspects of the invention reside in certain details of construction as well as the combination of parts to be described hereinafter in view of the drawing, in which:

Fig. 1 is a perspective view of the manikin per se;

Fig. 2 is a vertical sectional detail view through the manikin showing its connection with a drive means;

Fig. 3 is a vertical sectional detail view, partly in elevation, with the rear cover plate of the manikin removed and as seen along line 3—3 in Fig. 2; and

Fig. 4 is a skeletonized perspective view of the essential drive connections of the manikin structure illustrative of the body movement thereof.

Referring to Fig. 1, the manikin structure of the present invention is indicated at 10 and includes a fixed lower or nether portion 11 comprising the legs of the manikin. The legs are formed integrally with a base plate 12 in one unitary casting. The left leg 13 of the manikin is hollowed out to provide a tubular inner portion 14 (Fig. 2), which tubular portion extends downwardly beneath the base plate 12 to provide a tubular mounting 15. The tubular extension 15 is mounted in an upstanding boss 16 formed as a part of a mounting plate 17 which is adapted to be fastened to a ball playing surface (not shown). It is to be noted that the base plate 12 is pitched slightly with respect to the mounting plate so as to conform with 55

the inclined surface of the ball playing board upon which the manikin is adapted to be mounted. The inclination is necessary so that played balls may gravitate to an out pocket or any other suitable ball exit opening for return to a ball feeding means (not shown).

The trunk portion 18 is pivotally mounted as at 19 at the hipline of the manikin so that the manikin structure 10 may bend at the hipline to the dotted-line position, Fig. 1. The upper end of the nether portion 11 is provided with a trunnion 20 in which is mounted for rotatable movement a shaft 21. The outer ends of the shaft 21 have flattened surfaces 22 upon which are mounted the depending ears 23 of the trunk portion so that the trunk portion will rotate with the shaft 21. A hub structure 24 is fixedly mounted on the shaft 21 for rotation therewith and is provided with an enlarged disc formation 25 from which extends laterally an eccentrically mounted pin 26. A connecting rod 27 has an end portion 28 thereof looped about the eccentrically mounted pin 26 and has a lower end portion 29 fastened by a screw 30 within a yoke-formed block 31, which in turn is pivotally mounted as at 32 on a rocker arm 33 for reasons hereinafter to be explained.

The trunk portion 18 is hollowed out to provide a chamber 34 (Figs. 2 and 3) and provides at the shoulder portion 35 of the manikin a mounting for a shaft 36. A pulley 37 is fixedly mounted upon the shaft 36 for rotation therewith and has arranged in one flange portion 38 thereof a pin 39, which pin extends through the final loop of a flexible element 40, in the present instance in the form of a chain having a plurality of links. The opposite end 41 of the flexible element 40 is attached to a hook 42 formed on the upper end of a connecting rod 43 having its lower end 44 fixed by a screw 45 in a yoke block 46 pivotally attached to a rocker arm 47 for purposes hereinafter to become more apparent.

The right arm 48 of the manikin is fixedly attached to a keyed end 49 of the shaft 36 in such manner that rotatable movement of the shaft 36 will be imparted to the arm 48 to simulate a swinging or ball throwing action in the arm 48. This ball pitching arm 48 is normally held in ball-pitched position, as seen in Fig. 1, by a stop 50 formed on the trunk portion 18 (Fig. 3). The shaft 36 is normally urged into a position to dispose the arm 48 on the stop 50 by a coil spring 51 disposed on the shaft 36 and having one end portion hooked into a flange

52 formed as a part of the pulley 37 and its opposite end anchored as at 53 on a clip angle 54 fixedly arranged in the chamber 34 of the manikin trunk.

Any suitable drive mechanism may be employed to actuate the movable elements of the manikin structure and in the present instance there is shown (Figs. 2 and 3) a drive means in the form of an electric motor 55 having a speed reducing unit 56 associated therewith to provide a drive shaft 57 which will impart a uniform and relatively slow rotatable action. The shaft 57 is supported in a pair of bracket arms 58 depending downwardly from the mounting plate 17. The shaft 57 has arranged thereon a plurality of driving cams. One of the driving cams is indicated at 59 and is adapted to engage a roller 60 extending from and carried by the rocker arm 33 substantially beyond the point of pivot mounting of the yoke block 31 carried by the rocker arm 33. This rocker arm 33 is supported on a horizontal shaft 61 extending between the bracket arms 58. A spring 62 has one end attached as at 63 to the rocker arm 33 and its opposite end anchored as at 64 to the mounting plate 17 so as to normally urge the rocker arm 33 in a clockwise direction about the shaft 61. By reason of the operative connection of the rocker arm 33 with the hipline shaft 21 through the medium of the connecting rod 27, the trunk portion 18 of the manikin will be normally maintained in erect position (as shown in the drawing) through the action of the spring 62, such erect position of the trunk being limited so that the manikin trunk will not rotate in a backward direction beyond erect position.

Another cam, indicated at 65, is likewise mounted on the drive shaft 57 and is adapted to engage a roller 66 extending from and carried by the rocker arm 47, the latter in turn being rockably supported by the shaft 61 heretofore described. The rocker arm 47 is disposed in a normal position through and by virtue of the action of the pre-tensioned spring 51 arranged on the shoulder shaft 36 through the medium of the flexible element 40 and the connecting rod 43.

A third cam, indicated at 67, is provided with an irregular periphery and has a number of switches bearing against such periphery for the purpose of timing the cycle of operation imparted to the manikin structure in a manner well known in the art. In the present instance there is provided a holding switch 68 adapted to assume broken circuit condition as seen in Fig. 2, under normal circumstances. This switch 68 is disposed to be cammed into closed circuit condition as soon as the motor 55 has begun to operate a substantial amount. Such initial operation of the motor is accomplished by a hand-controlled switch 69 adapted to be disposed in closed circuit condition by a push button or any other suitable device so that the holding switch 68 may be cammed into circuit closing condition where it will remain throughout a complete revolution of the shaft 57 until the recessed formation 70 on the periphery of the cam 67 comes into alignment with the cam portion 71 of the switch 68.

Having described the structural characteristics of my new and improved manikin structure, a brief description of a cycle of operation will now be set forth so as to disclose the advantages of the present invention. The manikin is normally disposed in the position shown in Fig. 1, and when the player is ready to receive a pitched

ball, the push button is operated to dispose the switch 69 in closed circuit condition whereupon the motor 55 will be energized and the shaft 57 begin to rotate. After a slight initial movement of the shaft 57, the holding switch 68 will maintain the motor in energized condition so that the cams 59 and 65 will continue to rotate. The cam 59 will then engage the roller 60 on the relay arm 33, bearing down upon the roller 60 to rotate the rocker arm 33 in a counterclockwise direction (Fig. 2). Such movement of the rocker arm will cause a downward pulling action on the connecting rod 27, thus pulling downwardly on the laterally extending pin 26 eccentrically mounted on the disc 28 carried by the shaft 21. Such movement will be imparted to the shaft 21 and in turn to the trunk portion 18, so that the trunk portion will rotate into the position shown in dotted lines in Fig. 1, with the hand portion 72 of the arm 48 disposed over a ball opening 73 formed in the base plate 12. Simultaneously with the bending movement a ball will have been elevated to a position adjacent the hand by means not shown in the present disclosure. At the time the hand 72 reaches the position adjacent the opening 73, switch means 74 associated with the switch cam 67 will be disposed in closed circuit condition to supply current to a stationary contact 75 mounted within the chamber 34 of the trunk portion 18 through a conductor C and having its free end portion wipingly engaging a movable contact 76 in turn connected by a suitable conductor means 77 to a coil formed in the arm 48 to provide a magnetic field in the region of the hand 72, thereby attracting a steel ball disposed at the opening 73 into the hand 72.

The cam 59 continues its rotative movement, releasing the roller 60 and rocker arm 33 for return movement by action of the spring 62 so that the trunk 18 will return to erect position. During the return movement of the trunk 18 to erect position, the cam 65 engages the roller 66 on the rocker arm 47 to depress the end of the rocker arm 47 carrying the yoke block 46, whereupon the connecting rod 43 will be pulled downwardly and with it the flexible element 40, thereby pulling the pin 39, carried by the pulley 37, in a counterclockwise direction (Fig. 2).

The foregoing rotative movement of the pulley 37 is in turn imparted to the shaft 36, so that the arm 48 of the manikin will gradually swing toward the dotted line position with respect to the trunk 18 as the latter is returning to its erect position, at which time the arm 48 will have reached its maximum or ball pitching position as seen in dotted lines (Fig. 1). Upon the arm reaching its ball pitching position, the switch 74 will ride off the high point of the cam 59 to assume an open circuit condition, thus breaking the circuit to the coil within the arm 48 and releasing the magnetic attraction on the ball held within the hand 72. Subsequent to the foregoing operation, the cam 65 will abruptly release the roller 66, thus allowing the tensioned spring 51 to uncoil abruptly to swing the shaft 36 and the arm 48 into a normal position with the arm resting upon the stop 50. Such swinging action of the arm causing, by centrifugal force, a pitching of the ball in a predetermined trajectory.

The ball pitching arm may be provided with a permanent magnet, if desired, which has a relatively light magnetic attraction, such that upon the abrupt return action of the pitching arm 48 from ball pitching position toward ball-pitched

position the centrifugal force will be sufficient to release the ball from the hand 72.

The main object of the present invention is to provide a manikin structure having a bendable body to simulate the picking up of a ball and at the same time to provide a swinging arm to impart a pitching action to the ball. The arrangement of parts essentially necessary to the present invention is well illustrated in Fig. 4 as providing a relatively simple structure requiring a minimum of parts for accomplishing the result sought.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a pitcher manikin including a hollow body bendable at the hip and having a fixed nether portion and a mounting plate carrying said nether portion and supporting a drive means on the under side thereof, said nether portion having one leg portion in the form of a tubular member communicating with said hollow body and the under side of said mounting plate, together with a trunk portion arranged on said nether portion for rotatable movement with respect thereto, the combination of a horizontal shaft arranged on said nether portion, said shaft having operative connection with said trunk portion for imparting rotative movement thereto, a disc arranged on said shaft, a pin arranged on said disc eccentrically of said shaft, means extending downwardly through said tubular member for connecting said eccentrically arranged pin with said drive means, a second shaft horizontally arranged at the shoulder line of said trunk portion for rotative movement with respect thereto, a pitcher arm connected to said second shaft and adapted to swing from ball-pitched position to ball pitching position, spring means on said last-named shaft and normally urging the latter and said pitcher arm into ball-pitched position, pulley means fixed on said second shaft, a flexible element having one end portion trained over said

5 pulley a length greater than one-half the circumference of the pulley, the opposite end of said flexible element extending over said first-named shaft, a connecting rod arranged in said tubular member for vertical movement and connecting said flexible element with said drive means to rotate said second shaft and said pitcher arm into ball pitching position against the action of said spring means.

2. In a ball projecting mechanism, a base member on which a ball to be projected is adapted to be positioned, a manikin on said base member comprising a body including a fixed nether portion and a trunk portion on said nether portion 15 for movement about a pivoted axis and including a pivotally supported ball projecting arm and movable about said pivoted axis to a stooped position to dispose the said arm in position to pick up said ball from said base member, means for 20 pivotally connecting the arm to the trunk portion, means for pivotally moving the trunk portion about said axis into said stooped position, and means for pivoting said arm in ball projecting movement.

3. In a ball projecting device, a base member 25 on which a ball to be projected is adapted to be positioned, ball projecting means on the base member including a pivotally supported ball projecting arm adapted to be pivoted to a position 30 adjacent the said base member for receiving the ball positioned thereon, means for pivotally supporting said ball projecting arm, means for pivotally moving said ball projecting arm in said position to receive the said ball, and means for pivotally moving the ball projecting arm in ball projecting operation.

4. A projecting device comprising a body including a fixed nether portion, a trunk mounted on said portion and including a ball projecting 40 arm and movable about a pivotal axis to a stooped position to dispose said arm in position to receive a ball to be projected thereby, shaft means comprising said pivotal axis and pivotally connecting said trunk with said nether portion for 45 said movement, means on said shaft for rotation therewith and for pivoting said trunk to said stooped position, said means comprising an eccentric, drive means for operating said eccentric, and means connecting said eccentric with said drive means.

CLARENCE A. SCHUYLER.
